UNITED STATES PATENT OFFICE.

GEORGE CUSTER, OF WHITNEY, TEXAS.

FILE.

SPECIFICATION forming part of Letters Patent No. 295,487, dated March 18, 1884.

Application filed November 2, 1883. (No model.)

To all whom it may concern:

Be it known that I, GEORGE CUSTER, a citizen of the United States, and a resident of Whitney, in the county of Hill and State of Texas, have invented certain new and useful Improvements in Files; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of my improved file. Fig. 2 is an edge view of the same. Fig. 3 is an edge view of the edge opposite to that shown in Fig. 2, and Fig. 4 is a perspective view of the file.

Similar letters of reference indicate corresponding parts in all the figures.

My invention has relation to files; and it consists in the improved construction of the same, as will be hereinafter more fully described and claimed.

In the accompanying drawings, A represents the file proper. The teeth upon the sides of my improved file are cut in such a manner that they extend only half-way across the width of the file, the inner ends of the teeth meeting at an angle at the center of the width of the blade. By this arrangement of the teeth the file is made a self-cleaner—that is to say, it clears itself of its own dust or chips. One edge of the file (that edge shown in Fig. 3) is provided with a series of ordinary straight cuts or teeth, while the other edge is preferably made somewhat rounded, and provided

with a series of longitudinal cuts or teeth, as shown in Fig. 2.

From the foregoing description, taken in connection with the accompanying drawings, the construction of my improved file will readily be understood without requiring further explanation. By constructing the file-blade with the longitudinal teeth on its edges the operator can use the file for fine work, &c.

Having thus described my invention, I claim and desire to secure by Letters Patent of the United States—

1. A file provided with longitudinal teeth upon one or both of its edges, as described.

2. A file having the teeth upon its sides so cut that they extend only half-way across the width of the file, the inner ends of the said teeth meeting at an angle at the center of the width of the blade, as and for the purpose shown and set forth.

3. A file provided with longitudinal teeth upon one or both of its edges, and having the teeth upon its sides so cut that they extend only half-way across the width of the file, the inner ends of the said teeth meeting at an angle at the center of the width of the blade, constructed and arranged to operate substantially in the manner and for the purpose shown and set forth.

In testimony that I claim the foregoing as my own I have hereunto affixed my signature in presence of two witnesses.

GEORGE CUSTER.
